CLAIM

An ornamental design for an “over the shoulder harness/sling,” as shown and described.

DESCRIPTION

FIG. 1 is a front perspective view of a first embodiment of the over the shoulder harness/sling;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a second embodiment of the over the shoulder harness/sling;

FIG. 9 is a front elevation view thereof;

FIG. 10 is an environmental perspective view thereof; and,

FIG. 11 is an environmental perspective view thereof.

The broken lines shown in the drawings represent portions of the over the shoulder harness/sling or environment that form no part of the claimed design.
